UNITED STATES PATENT OFFICE.

FABIAN ZEMOJTEL, OF PHILADELPHIA, PENNSYLVANIA, ASSIGNOR OF ONE-THIRD TO
JOSEPH SOBOLEWSKI, OF PHILADELPHIA, PENNSYLVANIA.

LAUNCHING DEVICE FOR AEROPLANES.

1,240,400.

Specification of Letters Patent. Patented Sept. 18, 1917.

Application filed July 20, 1917. Serial No. 181,787.

To all whom it may concern:

Be it known that I, FABIAN ZEMOJTEL, a citizen of Russia, residing at Philadelphia, in the county of Philadelphia and State 5 of Pennsylvania, have invented certain new and useful Improvements in Launching Devices for Aeroplanes, of which the following is a specification.

This invention relates to certain new and 10 useful improvements in launching device for aeroplanes.

The primary object of the invention is the provision of a ready means for launching aeroplanes in a safe manner either from 15 hangars or from shipboard, the final supporting portion of the launching means being arranged to permit of an even travel of the craft thereover.

A further object of the device is to provide 20 a launching platform for aeroplanes whereby the latter may be expeditiously and safely started in its flight, adjustable resilient supporting means being arranged for the aeroplane during the latter portion of 25 its travel over the device.

With these general objects in view and others that will appear as the nature of the invention is better understood, the same consists in the novel combination and arrangement of parts hereinafter fully described, illustrated in the accompanying drawing and pointed out in the appended claim.

In the drawing forming a part of this application like designating characters refer 35 to corresponding parts throughout the several views and in which—

Figure 1 is a side elevation of the device, illustrating its use in connection with an 40 aeroplane,

Fig. 2 is a top plan view thereof and

Fig. 3 is a vertical central sectional view through a forward portion thereof.

It will be understood that the present device 45 being designed for launching aeroplanes may be employed upon shipboard or any other place desired such for instance as in connection with the hangar 10. A platform 11 extends forwardly of the hangar from a point on a level with the floor thereof as at 12 and gradually slopes upwardly 50 in the general form of a parabolic curve. Suitable supporting means 13 are provided for the platform while a frame 14 extends

forwardly therefrom having a forward free-end section 15 of the platform resiliently mounted thereon.

The platform section 15 is hinged as at 16 to the main portion of the platform having a terminal rear-edge 17 preventing the section 15 from moving upwardly out of the general curvature of the complete platform. Adjusting screws 18 are threaded through bushings 19 in the top 20 of the frame 14 while the springs 21 are tensioned 65 between the heads 22 of the screws 18 and blocks 23 upon the bottom of the section 15. Handles 24 are arranged on the bottoms of the screws 18 whereby the latter may be readily adjusted from points beneath the 70 frame top 20.

The complete operation of the device will be apparent from this detailed description thereof, it being understood that the aeroplane such as 25 being adapted for storing 75 in the hangar 10, may move outwardly thereof upon the platform 11 passing upwardly thereover at an increasing rate of speed which still increases when passing over the section 15, the resistance to the 80 movement of the aeroplane being lessened by the depressing of the section 15 which permits the speed of the craft to further increase although affording sufficient support therefor during the latter portion of its 85 travel over the device. The tension of the spring 21 is regulated by turning the handle 24 for accommodating aeroplanes of different weights. An advantageous manner of launching aircraft is arranged tending to- 90 ward assisting the speed as well as the safety of the initial portion of the flight.

The form of the invention herein illustrated is believed to be preferable although minor changes may be made without departing from the spirit and scope of the invention as claimed.

What I claim as new is:—

A device of the class described comprising in combination with a hangar, a platform leading from a point adjacent the floor thereof extending forwardly and upwardly in a parabolic curve, the said platform having a forward hinged portion, means for preventing the upward swinging 100 movement of said portion above the plane of the general curvature of the platform, supporting means for the platform having 105

its forward portion in the form of a frame with its top positioned beneath said hinged portion, bushings extending through said top, adjusting screws threaded through said 5 bushings, and having heads above said top, blocks upon the bottom of said portion, springs arranged between the said heads

and blocks and operating handles for said screws arranged beneath the said top.

In testimony whereof I affix my signature 10 in presence of a witness.

FABIAN ZEMOJTEL.

Witness:

T. HRYCEY.
